UNITED STATES PATENT OFFICE.

MILES WILSON, OF CANASTOTA, NEW YORK, ASSIGNOR TO GEORGE E. CHAMBERS, OF ONEIDA, NEW YORK.

DESIGN FOR A TOOTHPICK-VENDER.

58,653.

Specification for Design.

Patented Aug. 2, 1921.

Application filed March 8, 1921. Serial No. 450,638. Term of patent 14 years.

To all whom it may concern:

Be it known that I, MILES WILSON, a citizen of the United States, residing at Canastota, in the county of Madison and State of New York, have invented a new, original, and ornamental Design for Toothpick-Venders, of which the following is a specification, reference being had to the accompanying drawing, forming part thereof.

The figure is a plan view of a tooth-pick vender showing my new design.

I claim:

The ornamental design for a toothpick vender as shown.

MILES WILSON.
